UNITED STATES PATENT OFFICE.

ISRAEL HAYES, OF FARMINGTON, NEW HAMPSHIRE.

IMPROVED SHOE-SHAVE.

Specification forming part of Letters Patent No. 44,420, dated September 27, 1864.

To all whom it may concern:

Be it known that I, ISRAEL HAYES, of Farmington, in the county of Stafford and State of New Hampshire, have invented a new and Improved Shoe-Shave; and I do hereby declare that the following is a full, clear, and exact description thereof, which will enable those skilled in the art to make and use the same, reference being had to the accompanying drawings, forming part of this specification, in which—

Figure 1 is a side view of my invention; Fig. 2, a face or under view of the same; Fig. 3, a transverse section of the same, taken in the line *x x*, Fig. 2; Fig. 4, a detached side view of the guard-plate pertaining to the same.

Similar letters of reference indicate corresponding parts.

This invention relates to a new and improved device for shaving the soles and heels of boots and shoes.

The object of the invention is to obtain a shoe-shave which will operate equally as well on the heels of boots or shoes as on the edges of the sole, and which will work perfectly in the hollow or shank without interfering or coming in contact with the upper, as hereinafter set forth.

A represents the stock of the shave, which is constructed of wood, one part, *a*, of which constitutes the handle and is so curved or formed as to be conveniently grasped in the hand. The central part, *b*, projects down below *a*, and has its under surface curved longitudinally, as shown in Fig. 1, and it is beveled transversely at its rear, as shown at *c* in Fig. 3. To the under surface of *b*, in front of the beveled part *c*, there is secured a metal plate, *d*, by means of screws *e e*. The other part, *f*, of the stock projects from the upper end of the part *b*, and is nearly or quite straight, *b* projecting down some distance below *f*, forming a curve, *g*, at their junction, as shown in Fig. 1.

B represents a knife, which is curved to correspond to the curvature of the under sur-

face of *b*. This knife is bent upward at one end, and is rounded to form a shank, *h*, which is fitted in the part *b*. The opposite end of the knife is secured by means of a small hook or catch, *i*, to the lower end of a plate, *C*, which passes vertically through *b* at its junction with *f*, said plate having a rod at its upper end, on which a screw is cut to receive a thumb-nut, *D*.

The plate *C* has an oblong hole made in it, through which a screw, *j*, passes into the end of *b*, to serve as a guide.

The plate *C* serves as a guard or guide for the knife *B*, its outer surface bearing against the leather or upper of the boot or shoe.

The bottom or under surface of the knife is rounded near the plate *C*, as shown at *k*; so is the plate *d*. These rounded surfaces admit of the knife *B* being turned so as to conform to the edge of the sole all around and in the shank or hollow of the same, while the part *a* of the stock, in consequence of being up some distance above the part *b*, will not come in contact with the upper of the boot or shoe.

The cut of the knife may be regulated by turning the thumb nut *D*. The whole device is extremely simple and efficient, and possesses the advantage of being capable of being used for shaving the sides of both the sole and heel of a boot or shoe.

I claim as new and desire to secure by Letters Patent—

1. The knife *B*, fitted to the part *b* of the stock, as shown, and connected with an adjustable guard-plate, *C*, all arranged and applied substantially as and for the purpose herein set forth.

2. The rounding of the under surface of the knife *B* and the plate *d*, substantially as and for the purpose set forth.

3. Constructing the stock *A* of three parts, *a b f*, curved substantially in the manner as and for the purpose specified.

ISRAEL HAYES.
